UNITED STATES PATENT OFFICE.

WILLIAM H. NICHOLS, OF TWIN LAKE, INDIANA.

THILL-COUPING.

SPECIFICATION forming part of Letters Patent No. 638,936, dated December 12, 1899.

Application filed March 21, 1898. Serial No. 674,699. (No model.)

To all whom it may concern:

Be it known that I, WILLIAM H. NICHOLS, a citizen of the United States, residing at Twin Lake, in the county of Marshall and State of Indiana, have invented a new and useful Improvement in Thill-Couplings, of which the following is a specification.

My invention relates to thill-couplings; and its object is to provide an improved construction of the same by which the thills can be readily attached to and detached from the axle-clip and by which rattling will be effectually prevented.

The invention consists in the novel construction and combination of parts hereinabove fully described and claimed.

In the accompanying drawings, Figure 1 is a perspective of a thill-coupling constructed in accordance with my invention, showing the same closed. Fig. 2 is a similar view showing the same opened. Fig. 3 is a detail view.

In the said drawings the reference-letter A designates the clip, the lower plate of which extends rearwardly, forming a projection, with which a spring-catch, hereinafter described, engages. Formed integral with said clip is a long arm 13, formed in its upper side with a slot or recess 2. Said clip is also formed with a short arm 7, with which is pivotally connected by a pivot 8 a slotted bar 11, provided with a pin 1, adapted to engage with the eye of an ordinary thill-iron and also adapted to engage with the slot or recess 2.

4 designates a lever having a curved head 4^a formed with a curved slot 3. This lever is supported between the bar 11 and the arm 13 by means of the pivot 8 and a pivot-pin 12, the latter projecting from the arm 13 into one side of the slot 3, while the reduced end 9 of the pivot 8 projects into the opposite side

of said slot 3. A spring-catch 5 projects from the lever 4 and is adapted to engage a groove 6 in the lower plate of the clip.

The operation is as follows: To connect the thill, the lever 4 is thrown down into the position shown in Fig. 2 and the pin 1 is passed through the eye of the thill. The said lever is then pushed upwardly, as shown in Fig. 1, and the spring 5 engaged in the groove 6. The thills will be now securely connected with the axle without any liability of accidental disengagement. Rattling will also be prevented.

Having thus fully described my invention, what I claim is—

1. In a thill-coupling, the combination with a clip, the upper member of which is formed with a slotted long arm, and a short arm parallel to said long arm; and the lower member of which is extended rearwardly and grooved; of a slotted bar pivotally secured to the short arm of the clip and provided with a transverse pin; a lever provided with a spring-catch and a slotted curved head, the latter being supported by oppositely-disposed pins between the long arm of the clip and the pivoted slotted bar.

2. In a thill-coupling, the combination with a clip having parallel arms projecting from the front side thereof, one of said arms being longer than the other and formed with a slot, of a slotted bar pivotally secured to the short arm of the clip and carrying a thill-securing pin; a lever supported between the long arm of the clip, and the slotted bar, and having a head formed with a curved slot; fulcrum-pins for said lever, and means for securing the lever in engagement with the lower plate of the clip.

WILLIAM H. NICHOLS.
